FLUID REGULATORS

Yves Conan, Enghien, France, assignor to Bronzavia S.A., Courbevoie, France, a French company

Filed Jan. 9, 1958, Ser. No. 707,998

7 Claims. (Cl. 121—42)

The present invention relates to regulators more particularly for regulating the inlet device controlling the supply of motive fluid to a machine (for example an air turbine) which drives another machine (for example, a dynamo (alternator, or pump) which must rotate at constant or substantially constant speed notwithstanding variations in the load. The object of the invention is to provide improvements in this type of regulator.

The regulator embodying the invention, which is of the type having a fluid relay comprising driving means for controlling said inlet device of the machine to be regulated, a control fluid distributor connected to the driving means for supplying the control fluid to the latter, and control means which are responsive to the speed of rotation of the machine to be regulated and actuate the fluid distributor and are operatively connected to the machine to be regulated, is characterized in that its constituent parts, namely the distributor, the driving means fed by the distributor and the control means for the distributor, are grouped in a common housing so as to form a compact unit capable of being mounted and dismounted in one piece relative to the machine to be regulated; whereby the passageways connecting the distributor to the driving means are as short as possible and the means constituting the reaction linkage (feed-back of the driving means to the distributor) are also as short as possible, which results in great sensitivity, great precision and rapid response of the apparatus.

In a preferred embodiment, the fluid regulator has the following improvements and combinations thereof:

(a) The driving means comprise a cylindrical chamber which is formed in the regulator housing and is provided with a diametral wall; pivotable in the chamber in a fluid-tight manner is a double blade rigid with a shaft disposed in the axis of the chamber, this double blade dividing, in co-operation with said wall, the cylindrical chamber into four compartments which communicate with the distributor in groups of two diametrically opposed compartments.

(b) The shaft of the double blade extends through a cover closing the cylindrical chamber and carries a device such as a lever adapted to control, through the medium of a suitable transmission, the inlet device of the machine to be regulated.

(c) The distributor comprises: a cylinder recess whose axis is preferably at 90° to the axis of the cylindrical chamber of the double blade; a fixed tube or sleeve having annular recesses and held in fixed position in a fluid-tight manner in said cylindrical recess; an intermediate sleeve having annular recesses and axially movable in the tube, its movement being a function of the movement of the double blade; and an inner piston or slide which have annular recesses, slides in the intermediate sleeve and is actuated by the control means responsive to the speed of the machine to be regulated.

(d) The shaft of the double blade extends into the cylindrical recess of the distributor and carries an eccen-

2

tric crank pin engaged without play in a recess in the intermediate sleeve so as to impart longitudinal movement to this sleeve as a function of the angular movement of the double blade.

5 (e) The control means responsive to the speed of the machine to be regulated—which comprise a driving rotor actuated by said machine, balls driven in rotation by the rotor and a cup having an inclined face on which the balls act in opposition to the force exerted by a calibrated spring—are disposed in axial alignment with the longitudinal axis of the piston or slide of the distributor.

10 (f) The cup of the control means responsive to the speed of the machine to be regulated is unitary with the slide of the regulator.

15 (g) A correcting or compensating device responsive to the temperature is provided for compensating the expansion due to the heating of the housing and for maintaining constant the overall length, and in consequence the compression, of the spring of the regulator.

20 (h) The compensating device comprises a chamber filled with liquid and closed by an elastically yieldable diaphragm on which is mounted the device serving as a support for one end of the spring of the regulator.

25 Further features and advantages of the invention will be apparent from the ensuing description of one embodiment of the regulator, with reference to the accompanying drawings, to which the invention is in no way restricted.

In the drawings:

30 Fig. 1 is plan view of a regulator, the cover of the driving means having been removed;

Fig. 2 is a sectional view taken along line II—II of Fig. 4;

Fig. 3 is a sectional view taken along line III—III of Fig. 4 which is at 90° to line II—II;

35 Fig. 4 is a sectional view taken along line IV—IV of Fig. 3;

Fig. 5 is a sectional view taken along line V—V of Fig. 2;

Fig. 6 is a sectional view taken along line VI—VI of Fig. 2;

40 Figs. 7 and 8 are half-sectional views, taken along lines VII—VII and VIII—VIII respectively of Fig. 5, and,

Fig. 9 is a diagram of a unit comprising the regulator, the machine to be regulated and the feed means for feeding liquid motive fluid to the regulator.

45 The regulator, the whole of which is indicated by A on Fig. 9, is intended to control, through a stop-valve B actuated by the shaft 6 of the regulator, the intake of a motive fluid (such as compressed air) entering the duct b and intended to feed a machine C, for example a compressed air turbine. Said machine drives, by means of the pinions c and 25, the rotating parts, hereafter described, of the regulator A. The machine C further drives a liquid pump 32, which, by means of the exhaust pipe 31, sucks up in the tank 30, the liquid, oil for example, and delivers said liquid, through the duct 33, to the regulator A. The liquid evacuated from the regulator returns to the tank 30, by means of the discharge duct 34.

50 As it can be seen on Figs. 1 to 8, the regulator embodying the invention comprises a housing 1 in one face of which is formed a recess or housing 1a adapted to receive a cup or cylindrical chamber 2 which is ordinarily closed by a cover 3 and in which is pivotable about the axis of said chamber, a double blade 4 which is rigid with a hub 5 and with a shaft 6 so that the chamber 2 is constantly divided into two parts separated from one another in as fluid-tight a manner as possible.

55 Also provided in the chamber 2 is a diametral fixed partition or wall formed by two partitions 7 extending

from the periphery of the chamber to the hub 5, the arrangement being such that the chamber 2 is constantly divided into four compartments of variable volume separated from one another in a fluid-tight manner, opposed compartments communicating with one another, through ducts which may be provided in the cover 3, and with the distributor described hereinafter through passageways *d* and *e* formed in the housing 1.

The shaft 6 extends through the cover 3 and is adapted to receive a control member, for example a lever (or crank) which is connected, by a link or any other transmission means, to the inlet control device B of the machine C to be regulated.

Provided in the housing 1 is a cylindrical bore or recess 8 having an axis perpendicular to the axis of the chamber 2. Permanently fixed in this bore is a tube 9 which is provided on its outer face with five annular recesses *f*, *g*, *h*, *i*, *j* with which communicate passageways formed in the housing 1, namely the inlet passageway *k* communicating with the recess *h* and with the duct 33 leading to the feeding pump 32 of the regulator, the return passageway *l* which communicates with the recesses *f* and *j* and with the duct 34 leading to the tank 30 of said pump, and the passageways *d* and *e* leading to the recesses *g* and *i* and to the compartments of the chamber 2. Radial ports put these various annular recesses into communication with the inner face of the tube.

Slidably mounted in the tube 9 in a fluid-tight manner is a controlled intermediate sleeve 10 whose outer face is provided with five annular recesses *m*, *n*, *o*, *p*, *q* which communicate through radial ports with the inner surface of the sleeve and which co-operate with the radial ports in the tube 9. The sleeve 10 has, at its inner end, an aperture in which is engaged without play an eccentric crankpin 11 carried by a shaft 12 rigid with the hub 5.

When the unit comprising the elements 4, 5, 6, pivots, the sleeve 10 is displaced in one direction or the other, axially of the tube 9 and varies the effective opening of the radial ports in this tube.

Slidably mounted in the sleeve 10 is the distributor piston or slide 13 whose periphery comprises three annular distributing recesses *r*, *s*, *t* arranged to co-operate with the radial ports of the sleeve 10.

The distributor slide 13 is hollow and encloses a return spring 14 which tends to shift it in the direction of the rotor controlling the regulation, described hereinafter. One end of the spring 14 bears against a cap 15 which, through the medium of a ball 16, exerts an axial thrust on the end 13a of the slide 13, whereas the other end of the spring bears against a flange on a tapped sleeve 17 which is held stationary as concerns rotation by a suitable guiding arrangement and in which is engaged an adjusting screw 18 which permits regulating the compression of the spring 14, that is, the speed at which the machine to be regulated must run.

The end 13a of the slide is in the form of a cup having a substantially frusto-conical form which the cup 19 of a driving head 20 surrounds, the driving head 20 having a shaft 20a which is supported by anti-friction bearings, such as ball bearings 21 and 22, in a recess 23 in alignment with the recess 8, the cup 19 rotating in a thrust ball bearing 24.

At its outer end, the shaft 20a carries a driving gear 25 to permit driving the rotating elements of the regulator by means of the gear *c* of the machine C to be regulated, whereas the driver 20 is arranged to drive in rotation the balls 26 which bear against the cup 19 and against the frusto-conical face of the end 13a, the arrangement being such that the distributor slide is biased toward the right (as viewed in Fig. 3) in opposition to the action of the return spring 14 under the effect of the centrifugal force exerted by the balls 26.

To avoid faulty regulation due to a rise in temperature of the body of the regulator (which frequently occurs in practice), the adjusting rod or screw 18 is combined

with a correcting or compensating arrangement comprising a chamber 18a which is filled with oil and closed by a diaphragm 18b welded on a collar 18c which is rigid with the rod 18 as concerns axial movement of the latter.

5 The diaphragm is maintained clamped between the tube 9 and the end cap 18d of the housing 1, and it receives the thrust of the spring 14 through a shoulder on the rod 18 which acts on the collar 18c.

When the housing 1 lengthens as result of expansion 10 due to the heat, the overall length of the spring 14 also lengthens and the compression of the spring decreases. But the oil in the chamber 18a also increases in volume and, through the medium of the diaphragm 18b, shifts the collar 18c which acts in turn on the spring 14 through the medium of the rod 18 and the tapped sleeve 17 and causes the spring to resume its initial compression.

The balls, which are thrown outwardly by centrifugal force, therefore conserve the same position and thus the speed remains constant.

The chamber 18a is filled and drained through two apertures which are formed in the cap 18d and are closed by screws 18e.

In a few words, the above described regulator works as follows:

25 When the machine C runs at the desired speed, the sleeve 10 and the piston 13 are, for example, in the position shown on Figs. 2, 3, 7 and 8. In said position, the passageways *d*, *e* are isolated from the ducts *k* and *l* because the ribs between the annular recesses *r*, *s*, *t* of the piston 13 obturate the radial ports in communication with the annular recesses *g*, *n* and *p*, *i*.

If the machine C accelerates, the balls 26 thrust back the piston 13 which (in the new position) opens the communication, through the annular recess *s*, between *h*, *o* and *p*, *i*, so that motive liquid coming from the pump 32 is admitted, from the duct *k*, to the duct *e* and enters in two opposite compartments of the chamber 2. Simultaneously, the two other opposite compartments of the chamber 2, connected to the duct *d* are put in communication with the duct *l* (and the discharge pipe 34) in consequence of the communication between *g*, *n* and *m*, *f*, through the annular recess *r* of the piston 13.

Thus, the double blade 4 rotate in the direction corresponding to the closing of the stop valve B and the machine C slows down.

45 But, in consequence of the rotational movement of the blade 4, the eccentric crankpin 11 moves the sleeve 10, so that the radial ports of said sleeve are again obturated by the annular ribs, between the annular recesses *r*, *s*, *t*, of the piston 13, so that the movement of the blade becomes stopped for limiting the closing motion of the stop valve B.

If the speed of the machine C decreases, the piston 13 moves to the left and the compartments of the chamber 2 are connected with the ducts *k* and *l* (that is to say respectively with the pump 32 and the discharge pipe 34) but in the opposite direction (with respect to the first direction) in order to increase the opening of the stop valve B.

50 Although specific embodiments of the improvements of the invention have been described, many modifications and changes may be made therein without departing from the scope of the invention as defined in the appended claims.

60 What I claim is:

1. In a fluid regulator for a machine to be regulated and having: a housing; driving means having a rotatable shaft and disposed in the housing for controlling said machine; a fluid distributor for distributing fluid under pressure disposed in the housing, connectable to a source of fluid under pressure and connected to the driving means so as to supply fluid under pressure to the driving means; control means disposed in the housing, responsive to the speed of said machine, operatively connected to said machine and operatively connected to the

distributor for controlling the latter in accordance with the speed of said machine; elastically yieldable return means acting in opposition to the means responsive to speed; said distributor comprising: a cylindrical recess in the wall of which communicates through passageways formed in the housing with the driving means and with the source of fluid under pressure; a fixed cylindrical tube having an outer face which is in contact with the inner face of the cylindrical recess and which has outer annular recesses which are in communication with said passageways, said annular recesses communicating, through radial ports formed in the wall of the tube, with the inner face of the latter; an intermediate cylindrical sleeve axially movable in the tube and operatively connected to the shaft of the driving means, the outer face of the sleeve being in contact with the inner face of the tube and having annular recesses which are capable of communicating with the radial ports of the tube and which communicate through radial ports formed in the wall of the sleeve with the inner face of the latter; and a cylindrical slide slidably mounted in the sleeve, having its outer cylindrical face in contact with the inner cylindrical face of the sleeve and having annular recesses which are in communication with certain of said radial ports formed in the sleeve, said slide being operatively connected to the control means responsive to the speed of said machine.

2. A fluid regulator as claimed in claim 1, wherein said shaft comprises an eccentric crankpin and the sleeve comprises a recess in which the crankpin is engaged, whereby pivoted movement of said shaft imparts a longitudinal movement to the sleeve.

3. A fluid regulator as claimed in claim 1, wherein said means responsive to the speed of said machine comprise: a rotor which has a driving head, is co-axial with the distributor and is operatively connected to said machine; balls disposed in such manner as to be driven by the rotor; a cup having an inclined face disposed in axial alignment with the rotor in front of the driving head and operatively connected to the slide and so constructed and arranged that the balls driven in rotation by the driving

head are capable of acting under the effect of centrifugal force on the cup axially of the cup in opposition to the action of said elastically yieldable return means.

4. A fluid regulator as claimed in claim 3, wherein said cup is integral with said slide.

5. A fluid regulator as claimed in claim 1, wherein said elastically yieldable return means comprise: a helical spring which is disposed inside the slide which is hollow, one end of the spring exerting an axial pressure on the slide; a screw-threaded sleeve which is disposed inside the slide and against which the other end of the spring bears; and an adjusting screw journaled in said housing and screw-threadedly engaged in the screw-threaded sleeve.

6. A fluid regulator as claimed in claim 5, further comprising compensating means responsive to heat and adapted to act on said screw so as to compensate for the elongation due to heat, of the housing and to thus maintain the force exerted by the spring constant.

7. A fluid regulator as claimed in claim 5, further comprising a non-rotative support rigid with the adjusting screw as concerns axial movement; an elastically yieldable diaphragm whose central portion is connected to said support and whose periphery is connected to the housing, the diaphragm being disposed in the housing so as to define with a wall formed in the latter a chamber adapted to receive a liquid whose expansion under the effect of the heating up of the regulator exerts an axial thrust on the adjusting screw in the direction toward the spring.
